Specification of Letters Patent.

Patented May 2, 1922.

Application filed August 23, 1917. Serial No. 187,765.

To all whom it may concern:

Be it known that I, RALPH W. BUMSTEAD, a citizen of the United States, residing at Brookline, county of Norfolk, State of Massachusetts, have invented an Improvement 5 in Computing Machines, of which the following description, in connection with the accompanying drawing, is a specification, like characters on the drawing representing like parts.

This invention relates to computing machines of that type which are designed to perform operations in multiplication, and the general object of the invention is to 15 provide a novel machine of this type which is capable of rapid operations and is accurate in its results. The complete machine includes a selective setting mechanism by which the machine can be set to obtain the 20 product of any two predetermined numbers, a multiplying mechanism which performs an operation corresponding to multiplying each digit of one factor by all the digits of the other factor, a totalizing mechanism which 25 totals up or adds the individual products obtained by the multiplying mechanism, and an indicating mechanism to indicate such totals and give the final result.

The multiplying mechanism is so constructed 30 that the various operations of multiplying each digit of one of the two numbers or factors to be multiplied by all of the digits of the other number or factor are performed simultaneously, and as a result, the time necessary for performing the multiplying operations is the same regardless 35 of the number of digits in either of the two factors. By this means the speed of operation may be increased as it will 40 take no longer to set the machine to multiply large numbers together and then to operate it than it does to perform the same operations where the numbers to be multiplied together are small and have only one 45 or two digits.

In the preferred embodiment of my invention the various operations are controlled and performed largely by electrical means which is not only conducive to high speed 50 operation, but also to accuracy in results.

In order to give an understanding of my invention, I have illustrated in the drawings a selected embodiment thereof which will now be described, after which the novel 55 features will be pointed out in the appended claims.

Fig. 1 is a diagrammatic view showing some of the wiring circuits and illustrating more or less diagrammatically the connection between the setting mechanism, multiplying 60 mechanism, totalizing mechanism and indicating mechanism;

Fig. 2 is a vertical sectional view through a machine embodying my invention;

Fig. 3 is a section on line 3—3, Fig. 2; 65

Fig. 4 is a section on the line 4—4, Fig. 2, said section showing the totalizing mechanism;

Fig. 5 is a plan view of the product-representing members and controlling 70 mechanism therefor;

Fig. 6 is a diagrammatic view showing a device for multiplying or dividing by ten or multiples of ten.

Fig. 7 shows how the indicating magnets 75 48 may operate the keys of an adding machine;

Fig. 8 is a general view showing the keyboard mechanism of a device embodying my 80 invention.

As stated above, the complete machine includes a setting mechanism by which the machine can be set so as to multiply any two predetermined numbers together; a multiplying mechanism which operates to multiply simultaneously each digit of one number by all the digits of the other number; a totalizing mechanism which adds up the totals of the individual products thus obtained; and an indicating or recording 90 mechanism which indicates or makes a record of the product.

The multiplying mechanism is controlled by electrical circuits which are selectively closed by the setting mechanism, the construction being such that when the setting mechanism is actuated to set the machine for multiplying any two predetermined numbers together, the proper circuits are thereby closed to cause the multiplying mechanism 100 to actuate properly to perform the desired multiplying operation. The setting mechanism, therefore, includes a plurality of circuits and switches therefor which can be selectively actuated for closing the proper 105 circuits.

Setting mechanism.

In the illustrated embodiment of the invention, the setting mechanism comprises 110 two sets of switches, one set corresponding to one of the two factors or numbers to be

- multiplied and the other set corresponding to the other factor or number. Each set of switches comprises a plurality of groups of nine switches, each group representing the 5 nine digits of a particular denomination, that is, there is one group of nine switches representing the units denomination, another group of nine switches representing the tens denomination, another group of 10 nine switches representing the hundreds denomination, another group of nine switches representing the thousands denomination, etc. Any number of such groups may be used in each set, depending on the capacity 15 of the machine. In the drawings I have shown an arrangement whereby one set of switches contains four groups and the other set three groups which would give the machine a capacity capable of multiplying any 20 number with three digits by any number with four digits. The capacity of the machine can, however, be increased by simply adding other groups of nine switches in each set of switches.
- 25 In Fig. 1 I have indicated diagrammatically at 1 and 2 two sets of switches, the set of switches 1 having three groups therein and the set of switches 2 having four groups therein. The various groups of switches in 30 the set 2 are designated *a*, *b*, *c*, *d*, respectively, and those in the set 1 are designated *e*, *f*, *g*, respectively. Each group of switches *a*, *b*, *c*, *d*, *e*, *f*, *g* represents the nine digits and the individual switches of group *a* are 35 designated by the reference numerals *a'*, *a''*, *a³*, *a⁴* *a⁵* *a⁶*, *a⁷*, *a⁸*, *a⁹*, and those of group *b* are designated by the reference numerals *b'*, *b²*, *b³* . . . *b⁹*, and those of group *c* are 40 designated by the reference numerals *c'*, *c²*, *c³* . . . *c⁹*, etc. The *a* group and the *e* group of the two sets of switches are the units groups; the *b* group and the *f* group are the tens groups; the *c* group and the *g* group are the hundreds groups.
- 45 The various switches of the groups can conveniently be arranged somewhat on the order of the keys in an adding or other computing machine, that is, with the switches of any group in a vertical line and with 50 the switches of the various groups arranged in parallelism. With this arrangement the setting of the machine for multiplying any predetermined numbers together, such, for instance, as 346 and 1874, would involve 55 closing the switches *g³*, *f⁴* and *e⁵* in set 1 and the switches *d'*, *c⁸*, *b⁷* and *a⁶* in set 2.
- The switches may be closed by any suitable means, such, for instance, as by means of keys, one for each switch, arranged so 60 that when any key is depressed or actuated the corresponding switch will be closed. Such an arrangement is illustrated in Fig. 7 wherein the keys for the switches are illustrated. The keys of each group, such, for 65 instance, as the *a* group, or the *b* group, or

the *c* group, are all grounded on an insulated bar or member 404 which will be connected to the corresponding circuit 15. Each key has a contact arm 405 which when depressed is adapted to engage a contact arm 70 406 connected to another bar 407 which is insulated from the bars 404 but which is connected to the corresponding *l* circuit. Hence the depression of any key will close the circuits, as shown in the diagram Fig. 1. 75

Multiplying mechanism.

The switches of each group are connected in parallel in a circuit connection which leads to a selective magnet forming part of 80 the multiplying mechanism, and the similar switches of all the groups of each set are also connected in parallel in a circuit connection which leads to a sunflower switch indicated generally at 3. This sunflower 85 switch is provided with a circular series *h* of nine contacts corresponding to the nine digits of the groups of switches in set 1, and a second series of contacts *i* which are connected to the switches of set 2. The series 90 of contacts *h* comprise the nine contacts *h'*, *h²*, *h³*, *h⁴*, *h⁵*, *h⁶*, *h⁷*, *h⁸*, *h⁹*, and the contact *h⁹* is connected by a circuit connection 4 with the switches *e⁰*, *f⁰*, *g⁰*; the contact *h⁸* is connected by the circuit connection 5 with the 95 switches *e⁸*, *f⁸*, *g⁸*; the contact *h⁷* is connected by the circuit connection 6 with the switches *e⁷*, *f⁷*, *g⁷*; the contact *h⁶* is connected by the circuit connection 6 with the switches *e⁶*, *f⁶*, *g⁶*, and so on.

The series of contacts *i* are divided into nine groups corresponding to the nine contacts *h'*, *h²*, *h³* . . . *h⁹*, and each group of contacts is sub-divided into nine other smaller contacts so that there are nine small 100 contacts *i* opposite each of the contacts *h*. The nine contacts *i* of each group which correspond to any of the contacts *h* in turn correspond to the nine digits of each group of switches in the set 2 of switches, and the 105 similar contacts *i* of each of the nine groups are connected by bus-bars *k*. There are nine of these bus-bars, and for convenience, I have indicated them by the reference numerals *k'*, *k²*, *k³* . . . *k⁹*. The bus-bar *k⁰* is 110 connected to one of the contacts *i* opposite each of the contacts *h* and is also connected by the circuit connection *l⁰* to the switches *a⁹*, *b⁹*, *c⁹*, *d⁹*. Similarly, the bus-bar *k⁸* is connected to another contact *i* opposite each 115 contact *h* and is also connected by the circuit connection *l⁸* to the switches *a⁸*, *b⁸*, *c⁸*, *d⁸*; the bus-bar *k⁷* is connected to still another contact *i* opposite each contact *h* and is also connected by the circuit connection 120 *l⁷* to the switches *a⁷*, *b⁷*, *c⁷*, *d⁷*; the bus-bar *k⁶* is connected to another contact *i* opposite each contact *h* and is also connected by the circuit connection *l⁶* to the switches *a⁶*, *b⁶*, *c⁶*, *d⁶*, etc. The sunflower switch also 125 130

cludes a contact member or brush 8 which is secured to but insulated from an arm 9 mounted on but insulated from an actuating shaft 10. The contact 8 is provided with 5 two contact fingers which wipe over the contacts *h* and *i* as the shaft rotates, and said brush is continuously in electrical connection with a battery 11 or other source of electrical energy through a circuit connection 12, contact 120, insulated contact ring 10 121 and wire 122.

As stated above, all the switches of each group are connected by a circuit connection with a selective magnet, and with the arrangement shown, there are three selective magnets connected to the groups of switches 15 *e*, *f* and *g*, respectively, in set 1, and four selective magnets connected to the groups of switches *a*, *b*, *c*, *d* in set 2. The first-named selective magnets are designated 13^e, 13^f, and 13^g, respectively, and the other selective magnets are designated 14^a, 14^b, 14^c and 14^d. The group of switches *a* is connected to the selective magnet 14^a by the 20 circuit connection 15^a, the group of switches *b* is connected to the selective magnet 14^b by the circuit connection 15^b; the group of switches *c* is connected to the selective magnet 14^c by the circuit connection 15^c, and the 25 group of switches *d* is connected to the selective magnet 14^d by the circuit connection 15^d. Similarly, the groups of switches *e*, *f* and *g* are connected to their selective magnets 13^e, 13^f, 13^g by the circuit connections 30 15^e, 15^f, 15^g. The selective magnets are all connected to the battery 11 by a return wire 16. With this arrangement and assuming that it is desired to multiply 346 and 1874, the switches *g*^g, *f*^g, and *e*^g of set 1 and the 35 switches *d*^g, *c*^g, *b*^g and *a*^g of set 2 will be closed. The shaft 10 is then rotated through one complete revolution, during which the selective magnet 13^g will be energized when the contact 8 is passing over contact *h*^g; the 40 magnet 13^f will be energized when the contact 8 is passing over the contact *h*^f; and the magnet 13^e will be energized when the contact 8 is passing over the contact *h*^e. Similarly, the magnet 14^d will be energized 45 each time that the contact 8 passes over a contact *i* connected to the bus-bar *k*^d; the magnet 14^c will be energized each time that the contact 8 passes over each of the contacts *i* connected to the bus-bar *k*^c; the magnet 14^b will be energized each time that the contact 8 passes over each of the contacts *i* connected to the bus-bar *k*^b; and the magnet 14^a will be energized each time that the contact 8 passes over each of the contacts *i* connected to the bus-bar *k*^a. As a result, 50 each of the magnets 14^a, 14^b, 14^c, 14^d will be energized nine times during each revolution of the shaft 10.

In performing the operation of multiplying 55 1874 by 346, each of the digits 6, 4, 3 of

the smaller number is multiplied by all of the digits 4, 7, 8 and 1 of the larger number, and the products thus obtained are added up or totaled.

The selective magnets 13 and 14 are the 70 elements which control the multiplying operations, and the arrangement is such that when any one of the magnets 13^e, 13^f or 13^g is energized simultaneously with any of the magnets 14^a, 14^b, 14^c or 14^d, the multiplying 75 mechanism will be actuated to perform the operation of multiplying together the two digits represented by such magnets. Assuming that the switches of the setting mechanism have been set as above described, then as the 80 arm 9 rotates, the contact 8 will pass over a contact connected to the bus-bar *k*^g, while it is on each of the contacts *h*; but as only the the switches *g*^g, *f*^g and *e*^g are closed, the magnets of the 13 series will only be energized 85 when the contact 8 is passing over the contacts *h*^g, *h*^f and *h*^e. Consequently, while said contact 8 is thus passing over each of the contacts *h*^g, *h*^f and *h*^e, the magnets 13^e, 13^f and 13^g, respectively, will be energized. As 90 the contact 8 is passing over each of the contacts *h*^g, *h*^f and *h*^e, it will pass over contacts *i* connected to each of the bus-bars. When the contact 8 passes over the contacts *i* connected to the bus-bars *k*^g, *k*^f, *k*^g and *k*^a at the 95 time that said contact 8 is in engagement with the contact *h*^g, then the magnets 13^e will remain energized for a period of time while each of the magnets 14^a, 14^b, 14^c and 14^d is energized, and similarly when the contact 8 is passing over contact *h*^f, the magnet 13^f will be energized simultaneously with each of the magnets 14^a, 14^b, 14^c, 14^d, and when the contact 8 is passing over the contact *h*^g, the magnet 13^g will be energized 100 simultaneously with each of the magnets 14^a, 14^b, 14^c, 14^d. 105

The circuits controlling the multiplying mechanism are such that when the units magnet 13^e is energized simultaneously with each of the magnets 14, the multiplying mechanism is actuated to multiply six by each of the digits 4, 7, 8, 1, and when the tens magnet 13^f is energized simultaneously with each of the magnets 14, the multiplying 110 mechanism will be actuated to multiply the digit 4 by each of the digits 4, 7, 8, 1; and when the hundreds magnet 13^g is energized simultaneously with each of the magnets 14, the multiplying mechanism will be actuated 115 to multiply the digit 3 by each of the digits 4, 7, 8, 1.

Each magnet 13^e, 13^f, 13^g is provided with an armature 17 which is connected to the battery by a supply wire connection 18 and which is adapted to close against four contacts 19 corresponding to the four magnets of the 14 series. Each of the magnets of the 14 series is provided with an armature having three insulated contacts 20, 21 and 22. 130

The four contacts 19 of the units magnet 13^e are connected by circuit connections 23 with the four contacts 20; the four contacts 19 of the tens magnet 13^f are connected by circuit connections 24 with the four contacts 21; and the four contacts 19 of the hundreds magnet 13^g are connected by circuit connections 25 with the four contacts 22. The contacts 20, 21 and 22 of each of the magnets of the 14 series are adapted to engage other contacts 26, 27, 28 in circuit connections 30 leading to a plurality of actuating magnets 29 of the multiplying mechanism, the magnets 29 being all connected to a return wire 50.

The multiplying mechanism comprises a plurality of product-representing disks 310 loosely mounted on the shaft 10 and arranged in pairs, each disk having its periphery stepped, as shown in Figs. 1 and 2. The two disks of each pair are rigid with each other and are also rigid with a ratchet wheel 32 which is situated between them. The pairs of disks are loosely mounted on the shaft 10 which carries the arm 9 of the sunflower switch, each pair of disks being connected to said shaft by means of a spring 33 so that if the disks are left free they will be rotated by the shaft through the spring. The shaft 10 is rotated at a uniform rate from any suitable source of power. I have herein shown for this purpose a motor 34 operating a motor shaft 35 which has a worm 36 thereon that is adapted to mesh with a worm gear 37 fast on the shaft 10. The actuating magnets 29 are shown as arranged in two rows situated on opposite sides of the shaft 10, and the armature of each magnet is connected to a pivotally-mounted pawl 38, said pawl 38 co-operating with the ratchets 32. In the device illustrated there are twelve actuating magnets 29, and there is one pair of product-representing disks 310 and its ratchet wheel 32 for each of the actuating magnets 29. The construction is such that when any magnet 29 is energized, its pawl 38 will be drawn down into engagement with its corresponding ratchet 32, thus locking the corresponding product-representing disks from rotation with the shaft. During the time that any pair of disks is thus locked, the spring 33 for such disks will simply be wound up by the rotation of the shaft.

From the above it will be seen that whenever one of the magnets of the 13 series is energized simultaneously with one of the magnets of the 14 series, the result will be the closing of the circuit through one of the actuating magnets 29, and this in turn will result in causing the pawl 38 for said magnet to be brought into locking engagement with its ratchet 32, thus locking one of the pairs of product-representing disks from further rotation.

For the proper operation of the device it is essential that after each magnet 29 has been energized it should be maintained energized until the shaft 10 has completed its rotation. I accomplish this herein by providing a normally-open locking circuit for each magnet which is automatically closed when the armature for said magnet is attracted and which when closed connects said magnet to the battery 11 independently of the selective magnets 13 and 14. Each locking circuit includes an insulated contact 115 connected to the battery through a supply wire 31 and carried by the corresponding pawl 38 and a second contact 116 connected to the circuit connection 30. Each pawl is normally maintained in its raised position by a spring 93, and the construction is such that when any pawl is raised, the contact 115 carried thereby will be out of engagement with the corresponding contact 116 so that the locking circuit is open. When any magnet 29 is energized and its pawl 38 is moved downwardly into engagement with the ratchet 32, the contact 115 will be closed onto the contact 116, thus closing the locking circuit. The magnet will now be connected to the battery 11 through the locking circuit and will be maintained energized until the circuit is opened at the end of the cycle of operations, as will be presently described.

The pairs of product-representing disks 310 are so shaped and designed that each angular position of each pair of disks represents the product of some two numbers, and the position in which any pair of product-representing disks 310 is stopped is determined by the angular position of the shaft 10 at the time when the actuating magnet 29 for said disks is energized. This in turn is dependent upon the arrangement of the contacts *i*. The peripheral shape of the product-representing disks 310 has such relation to the position of the various contacts *i* that whenever any actuating magnet 29 is energized by the simultaneous energizing of a magnet in the 13 series and a magnet in the 14 series, the corresponding product-representing disks will be brought to rest in a position representing the product of the two digits represented by the closed switches in the sets of switches 1 and 2. Hence in the case of the example above assumed, to wit: that of multiplying 346 by 1874, the magnets 14^a, 14^b, 14^c, 14^d will be energized simultaneously with the magnet 13^e at such respective times in the rotation of the shaft 10 as to cause the four magnets 29 which are thus energized to bring the corresponding four pairs of product-representing or product-determining disks 310 to rest in such positions as to indicate the product of 6^a4, 6^b7, 6^c8, and 6^d1. Similarly, when the magnet 13^f is energized and the magnets 13^g

14^a, 14^b, 14^c, 14^d are also energized, the corresponding magnets 29 will be operated at such times in the rotation of the shaft as to bring the corresponding four pairs of disks 5 to rest in position to indicate the products of 4⁴4, 4⁷7, 4⁸8, 4¹1. During the time that the magnet 13^e is energized, each of the magnets 14^a, 14^b, 14^c, 14^d will also be energized and the corresponding magnets 29 10 will be actuated at proper times to lock the corresponding pairs of product-determining disks 310 in positions to indicate the products of 3⁴4, 3⁷7, 3⁸8, 3¹1. Thus in the example above cited when the shaft 10 has made 15 one complete revolution, all of the twelve pairs of disks 310 have been brought to rest in positions corresponding to or indicating the individual products of the digits of one factor multiplied by those of another factor.

20 *Totalizing mechanism.*

After the various pairs of product-determining disks are thus positioned, the totalizing mechanism is actuated to add up or 25 total the products thus obtained. This totalizing mechanism comprises a plurality of vertically-extending bars 39, one for each of the disks 310, said bars being mounted for vertical movement in suitable guideways 30 40. The bars are normally held in elevated position and after the disks 310 are all properly positioned, said bars 39 are lowered until they contact with the positioned disks. The positions which the lowered bars 39 35 thus assume gives the totals of the products. This is accomplished by the following mechanism:

41 indicate a plurality of spring-actuated drums which are loosely mounted on a shaft 40 42, each drum being acted upon by a spring 43 which tends to hold it in zero position. Each drum has wound thereon a cord 44 which is actuated by one or more of the bars 39. There are as many drums 41 as there 45 are possible digits in the complete answer.

With the arrangement herein illustrated, the largest numbers which can be multiplied together are one containing three digits and one containing four digits. The greatest 50 number of digits in any possible product will be seven, and I have accordingly shown seven drums 41. Each drum 41 is provided with a plurality of contact arms 45 which are adapted to wipe over a plurality of contacts 46 as the drum rotates, there being ten contacts 46 for each drum, nine of the contacts corresponding to the nine digits and the other contact corresponding to zero. Each of the nine digit-representing contacts 46 for any drum 41 is connected by a circuit connection 47 with one of nine indicator magnets 48 which in turn are connected to the battery 11 through circuit connections 49, 50, 16, which also include a 55 60 65 make-and-break device for purposes pres-

ently to be described. This make-and-break device is in the form of a rotatable disk 66 of insulating material mounted on a suitable shaft 67 and having in one face thereof a contact provided with a portion 68 of 70 relatively short radius, a portion 69 having a larger radius, and a portion 70 which extends clear to the periphery of the disk. The circuit connection 49 is provided with a brush 71 engaging the periphery of the 75 disk, and the circuit connection 50 leads to a brush 72 which has continuous contact with the contact plate. At each rotation of the disk, the contact 70 will engage the brush 71, thus connecting the circuit connection 49 to the battery through the wires 80 50 and 16. Each drum is also connected to the feeder 31 leading from the battery through suitable circuit connections 52 so that when any drum 41 is brought to rest 85 with any one of its arms 45 in engagement with one of the contacts 46, a circuit will be closed through the corresponding indicator magnet 48 whenever during the rotation of the disk 66 the contact 70 engages the 90 brush 71. As stated above, there are seven drums 41 each having its set of contacts 46 representing digits of different denominations, although only one such drum is shown in Fig. 1. There are, therefore, seven sets 95 or groups of indicator magnets 48 also representing digits of different denominations, as shown in Fig. 1, the individual magnets of each group being connected to the several contacts 46 of one of the drums 100 41, each group having nine magnets therein representing the nine digits.

Said drums 41 are connected to the bars 39 of the totalizing mechanism so that when the bars are lowered against the product-determining disks 310, the various drums 41 will be turned to bring the arms 45 thereof into engagement with the proper contacts 46 to cause the total product to be indicated by the magnets 48 which are thus 105 energized. One arrangement by which the movement of the bar 39 may be made to actuate properly the drums 41 is illustrated herein. Some of the bars 39 are provided with pulleys 53 around which pass the cords 110 44 leading to the drums 41. Other of the bars are provided with rack teeth 56 which mesh with pinions 57 carried by the frame, said pinions in turn meshing with rack teeth on other vertically-movable bars 58 115 120 that are slidably mounted in the frame. These bars 58 have pulleys 59 thereon over which the cords 44 pass. Whenever any bar 39 having a pulley thereon is moved downwardly, the corresponding cord 44 will be 125 actuated to turn the drum 41 to which it is connected, the amount of turning movement, of course, depending upon the extent of downward movement of the bar 39. When any one of the bars 39 which is con- 130

nected to the bar 58 by the rack-and-pinion connection is moved downwardly, said bar 58 will be moved upwardly, and since one of the cords 44 passes over the pulley there-
5 on, such upward movement of the bar 58 will actuate the cord to operate one of the drums 41. The arrangement of bars 39, 58 and cords is such that when the bars 39 are all moved downwardly into the posi-
10 tion determined by the product-determining disks 310, the combined action of the bars 39 and 58 on the cords 44 is to cause the drums 41 to be turned into a position to in-
15 dicate the total product. In the arrange-
ment herein shown the cord 44 from the first or units drum passes over a direction pulley 55, thence under a pulley 53 on the first bar 39, the end of the cord being se-
20 cured to the frame at 54. The cord 44 for the second or tens drum 41 passes over a direction pulley 55, thence under a pulley 53 on the second bar 39, thence over a pulley 59 on a bar 58 which is connected to the third bar 39, thence under the pulley 53 supported
25 on the fifth bar 39, the end of said cord be-
ing secured to the frame at 60. The pulley 54 for the hundreds drum 41 passes over the direction pulley 55, thence under a pulley 53 on the fourth bar 39, and thence
30 over a pulley on a bar 58 which is geared to the sixth bar 39, thence under a pulley on the seventh bar 39, thence over a pulley 59 on the bar 58 which is geared to the ninth bar 39, thence under the pulley 53 carried by the eleventh bar 39, the end of
35 said cord being fastened to the frame at 61. This cord thus passes over five different pulleys. Similarly, the cord 44 for the thousands drum 41 passes over six different
40 pulleys, said cord passing alternately over pulleys 53 and 59 and being fastened at its end to the frame at 62. The cord 44 for the ten thousands drum 41 also passes alter-
nately over five different pulleys, said cord
45 passing alternately over pulleys 53 and 59, and the end of the cord being fastened to the frame at 63. The sixth cord 44 for the hundred thousands drum passes over three pulleys, two of which are pulleys 53, and
50 one of which is pulley 59; the end of the cord being fastened to the frame at 64. The last cord 44 for the millions drum passes under one pulley 53 only on the last bar 39, the end of the cord being fastened to the
55 frame at 65.

With this arrangement it will be seen that whenever all of the bars 39 are moved downwardly into engagement with the disks 310, the movement of the drums at each end will
60 be controlled by the movement of the end bars 39 only. The extent of turning move-
ment of each of the intermediate drums, however, depends upon the extent of move-
ment of two or more of the bars 39, and this
65 arrangement permits the simultaneous add-

ing of all the individual products obtained by multiplying each digit in one factor by each digit in the other factor because the extent of movement of some of the drums is that due to the cumulative effect of the 70 movement of several of the bars 39.

Any suitable means for lowering the bars 39 into engagement with the product-deter-
mining disks 310 at proper intervals may be employed. In the construction herein 75 shown, the bars 39 are all pivotally connected at their upper end to levers 73 which in turn are pivotally mounted on a rod or bar 74 carried by the frame. The free ends of the levers 73 rest on a lifting bar 75 which 80 is connected by a connecting rod 76 with a crank 77 on a crank arm 78 that is fast on the shaft 67. When the machine is at rest the shaft 67 is in the angular position shown in Fig. 1, in which position the lift- 85 ing bar 75 is in its elevated position. In making each computation, the shaft 67 is rotated through one revolution, during which the lifting bar 75 is first lowered thereby permitting the levers 73 and bars 39 90 to descend into positions determined by the positioned product-determining disks 310 and is then raised to return said levers 73 and bars 39 to their normal position. This lowering movement of the bars 39 is properly 95 timed to occur just after the product-deter-
mining disks have been positioned so that after the multiplying operation has been performed, the lifting bar 75 is lowered, thus performing the operation of adding the various products, as above described.

The make-and-break device 66 is on the shaft 67 and the contact 70 is so positioned thereon that the circuit through the indicating magnets 48 will be established just 105 after the lifting bar 75 has been lowered thereby to permit the bars 39 to be properly positioned. The lowering of the bars 39 will, of course, rotate the various drums 41 so that when the brush 71 engages the contacts 70, the drums will be properly positioned with the arms 45 thereof resting on the appropriate contacts 46 to indicate the correct result.

In order to correctly perform the adding 115 operations when the sum of any two numbers exceeds ten, it is, of course, necessary to carry the ten into the next column. The adding mechanism I have herein illustrated is provided with a carrying mechanism 120 which will now be described. Associated with each of the cords 44 except the units cord is a carrying lever 79 pivotally mounted on the bar 74 and carrying at its end a pulley 80 which is situated above the cord 44. Each lever 79 is provided with a down-
125 wardly-extending portion 81 which is adapted to engage a controlling lever 82 that is pivotally mounted on a rod or shaft 83. Each controlling lever 82 is provided with a 130

stepped portion 84 with which the downwardly-extended portion 81 of the carrying lever co-operates. Each carrying lever is acted upon by a spring 85 which tends to draw it downwardly, such downward movement being arrested by the extension 81 with the stepped portion 84. When the extension 81 rests on the highest step of the stepped portion 84, the carrying lever will be situated with its pulley 80 out of contact with the cord 44. Means are provided so that each time any drum 41 is rotated to carry its contact 45 past all nine of the contacts 46, then the controlling lever 82 for the next adjacent drum will be pulled backwardly one step so as to allow the carrying lever for said next adjacent drum to drop one step, this operation resulting in the cord 44 for said next higher drum being bowed or bent downwardly by the pulley 80 a sufficient amount to advance said next adjacent drum one point. Each of the various controlling levers 82 is controlled as to its operation by a magnet 86 which is in a circuit 87 that is connected to a zero contact 88 associated with the drum of the next lower denomination and is also connected by the brush 89 with the contact or collector ring on the disk 66. When, therefore, any drum 41 is moved to bring one of its contacts 45 into engagement with the zero contact 88, the magnet 86 associated with the next higher drum will be energized. Each magnet 86 has an armature carrying a pawl 91 which is adapted to engage ratchet teeth 92 mounted on the controlling lever so that each time a magnet 86 is momentarily energized, the controlling lever 82 will be drawn backwardly one step. Each drum 41 is shown as having three contacts 45, and the contacts 88 and 46 are so arranged that as one contact 45 passes off from the "nine" contact 46, the next contact 45 will pass onto the zero contact 88. When, therefore, any drum is rotated to indicate a number greater than ten, one contact 45 will be carried over all the contacts 46 and the next contact 45 will be carried onto or over the contact 88. This operation will actuate the magnet 86 and controlling lever 82 to allow the carrying lever 79 to drop one step so that the pulley 80 thereon will bend the cord 44 of the drum 41 of the next higher denomination to cause said drum to turn one step forward, thus performing the carrying operation.

It will be understood, of course, that a carrying mechanism of this nature is associated with each of the drums 41.

The brush 89 is so arranged that it will contact only with the portion 69 of the contact carried by the disk 66, and as a result, the carrying magnets 86 can only be actuated when the lifting bar 75 is being lowered for the purpose of positioning the bars

39, this being the time when the adding operation is performed. During the time that the lifting bar is being raised the brush 89 is resting on the insulated portion of the disk 66. 70

With the arrangement shown, each contact 45 will pass over the zero contact 88 before it reaches the contacts 46, and in order to prevent the carrying mechanism from operating when the contact 45 first passes over the zero contact 88 at the beginning of the adding operation, I propose to arrange the parts so that normally each pulley 80 is situated a slight distance above its cord 44. As a result, at the first actuation of each magnet 86, the corresponding carrying bar will be lowered one step which is just sufficient to bring its pulley 80 into engagement with the cord 44, after which at each actuation of the magnet the pulley 80 will 85 bend the cord 44, thus performing the carrying operation.

The operation of performing a computation in multiplication involves first setting the instrument by closing the proper setting 90 switches and then rotating the shafts 10 and 67 through one complete revolution. The means provided for thus rotating the shafts is such that the shafts are brought to rest after the rotation is completed, and at this 95 time the circuits for all the magnets 29 are opened thereby de-energizing said magnets and allowing the pawls 38 to be restored to normal position through their springs 93. The opening of the circuits of the magnets 100 29 is accomplished by means of a switch 94 situated in the circuit connection 50 constituting the return circuit for the magnets 29. The switch 94 is normally closed, but as the shaft 67 completes its rotation, it 105 is momentarily opened, thus breaking the circuit for all the magnets 29. It will be noted from Fig. 1 that when the shaft 67 is at rest the crank arm 78 is just past the center. Thus during the final rotative movement of the shaft 67, the lifting bar 75 will be carried slightly above the position it occupies in Fig. 1. One of the levers 73 is provided with an extension 95 which is adapted to engage one of the contacts 94 just 110 as the crank 78 passes over the dead center and thus the circuit for the magnets 29 is broken, just before the shaft 67 comes to rest.

It is intended that the motor 34 shall be rotating continuously and I have provided 120 herein a novel mechanism for connecting the shafts 10 and 67 to the motor at proper times and for disconnecting them therefrom when said shafts have made one complete revolution.

Upon referring to Fig. 2, it will be seen that the worm gear 37 is recessed or cut away at 96 so that when the worm 36 occupies said recess the worm can rotate without rotating the worm gear 37 and shaft 10. To 130

connect the worm gear 37 to the worm, the former is moved forward sufficiently to bring its teeth into mesh with the worm 36. This is accomplished by a starting magnet 97 which is connected to a circuit 98 that may be provided with a push-button or any other form of circuit-closing device. The starting magnet 97 has an armature 99 to which is pivoted one end of a starting member 100, the other end of the member having a roll 101 thereon which is adapted to engage a tooth or projection 102 formed on a disk 103 that is rigid with the shaft 10. When the parts are at rest in their normal position, the roll 101 is just behind the tooth 102. When the starting magnet 97 is actuated, the starting member 100 is moved to the right, Fig. 2, which operation will cause the roll 101 to engage the tooth 102 and thus advance the disk 103 and shaft 10 sufficiently to bring the worm and worm gear into mesh, after which the shaft 10 will be rotated through one complete revolution until the recess 96 comes into line with the worm 36 again. The shaft 67 is also rotated from the motor shaft 35 by similar mechanism, said shaft having a worm gear 104 fast thereon which meshes with a worm 105 on the shaft 35. The worm 104 is also provided with a recess 106 in which the worm 105 is received when the shaft is in its initial position.

In the operation of the machine the shaft 67 is at rest while the shaft 10 makes its rotation and after the shaft 10 has rotated and the product-determining disks 310 are properly positioned, then the shaft 67 is rotated to cause the bars 39 to be actuated as above described. The mechanism herein shown is such that when the shaft 10 completes its rotation, the shaft 67 is automatically started. This is accomplished by a starting member 107 which is pivoted to the starting member 100 and is provided with a roll 108 that cooperates with a disk 109 fast on the shaft 67. Said disk has a notch 110 therein so situated that the roll 108 will occupy the notch when the shaft 67 is at rest with the worm 105 in a recess 106. The disk 103 on the shaft 10 is provided with a rise 111 situated so that the roll 101 will pass over the rise just before the shaft 10 comes to rest. The action of the rise 111 on the roll 101 is to force the starting member 100 downwardly in Fig. 2, and this operation will move the starting member 107 downwardly which will give to the disk 109 and shaft 67 a turning movement sufficient to bring the worm gear 104 into mesh with the worm 105. When the shaft 67 has completed its rotation, it will automatically be brought to rest by reason of the fact that the worm 105 will then occupy the recess 106.

I have above referred to the magnets 48 as indicating magnets, and any suitable means may be employed in connection with said magnets whereby when any particular mag-

nets are energized, the product represented thereby will be indicated. These magnets 48 may also be in the nature of recording magnets so that when the magnets representing the product of any two factors are energized, a record of this product will be made. One way in which this may be accomplished would be to have the magnets 48 arranged to control the computing mechanism of an adding machine, and this can be done by placing the magnets above the keys 401 of an adding machine so that when any magnet is energized, the armature or core thereof will operate to depress the key, as shown in Figs. 7 and 8. Where such an arrangement is adopted, then it is possible to perform a plurality of multiplying operations and to add up or totalize the various products.

Many adding machines are so constructed that the operations involved in adding a series of numbers consist in first actuating keys or other similar mechanism that controls the computing mechanism of the adding machine and then operating another key or similar device which makes a printed record. The device herein illustrated is constructed so that it can be used in connection with an adding machine of this type. The various magnets 48 are arranged to control the computing mechanism of the adding machine and in addition to these, I have illustrated another magnet 129 which will be arranged to actuate or control the printing key 402 of the adding machine. This magnet 129 is in a circuit 133 which connects with the battery and which has therein a contact 134 situated to be engaged by the contact 70 in the disk 66 just after said contact has engaged the contact 71 and closed the circuit connection 49. Hence when the machine is actuated to multiply any two factors together, the rotation of the shaft 67 and disk 66 will first operate the totalizing mechanism and will then operate to close the circuit 49, thus energizing the appropriate magnets 48 to indicate the product, and immediately after will close the circuit 133, thus energizing the actuating magnet 129 and causing the adding machine to make a printed record of the product.

The machine herein shown, therefore, not only computes the product of any two factors, but also makes a printed record thereof.

Many times in making mathematical calculations, it is desirable to discard insignificant decimals or to multiply or divide by ten or some multiple of ten. I have provided herein and have illustrated diagrammatically in Fig. 6 a device by which these results may be accomplished. Said device is in the nature of a plurality of transposing switches situated in the circuits 47 leading to the indicating or recording magnets 48, so that by operating the switches the magnets 48 of any denomination may be connect-

ed to the contacts 46 of the next higher or the next lower denomination. In Fig. 6 I have shown a switch device comprising nine connected bars 135, each carrying seven insulated contacts 136. There is one of these bars 135 for each of the horizontal row of magnets 48, and the various contacts 136 of each bar are connected to the various magnets of the corresponding row. The contacts 136 normally engage other contacts 137 which are connected to the wires 47 leading to the contacts 46. When the bars 135 are in their normal position shown in Fig. 6, the electrical connections will be the same as illustrated in Fig. 1. If it is desired to multiply by ten, it is simply necessary to move the connected bars 135 to the left one step, thus connecting the units contacts 136 with the tens contacts 137. To multiply by one hundred, the bars 135 will be moved two steps to the left. To divide by ten the bars 135 will be moved one step to the right, Fig. 6, and to divide by one hundred, the bars will be moved two steps to the right and so on. By this simple means insignificant decimals may be discarded or the product may be multiplied or divided by ten.

While the operation of the machine will be readily apparent from the above description, yet I will briefly summarize the cycle of operations in solving a problem in multiplication.

When the machine completes a cycle of operations, the shafts 10 and 67 will be at rest and the setting switches will all be open and the pawls 38 and the actuating magnets 29 will be raised. The first operation is to set the machine by closing those switches of sets 1 and 2 which indicate the digits of the two factors to be multiplied together. When the machine has been thus set the starting magnet 97 is energized by closing its circuit 98 thereby attracting its armature 99 and operating the starting member 100 to give the worm gear 37 an initial movement sufficient to bring it into mesh with the worm 36. The shaft 10 thus becomes coupled to the continuously-rotating motor shaft 35, and said shaft will make one complete revolution at the end of which it is automatically brought to rest. During this rotation the brush or contact 8 wipes over the contacts *h* and *i*, thus closing simultaneously selected circuits through the magnets of the 13 series and 14 series which correspond to the closed switches. The simultaneous energizing of the magnets of the 13 series with those of the 14 series establishes circuits through appropriate actuating magnets 29 at proper time intervals so that the proper product-representing disks 310 will be brought to rest to indicate the individual products of each digit of one factor multiplied by those of the other factor.

As soon as the shaft 10 has completed its

revolution the shaft 67 is coupled to the motor shaft 5 and started in rotation, and during the rotation of the shaft 67 the lifting bar 75 is first lowered thereby to permit the various bars 39 to be lowered into contact 70 with the product-representing disks. This downward movement of the bars 39 operates through the cords 44 to rotate the drums 41 so that the various drums 41 are brought to rest in various positions indicating the digits 75 of the sum of the individual products obtained by multiplying each digit of one factor by all the digits of the other factor. After the bars 39 and drums 41 have thus been positioned, the contact 70 comes into engagement with the contact 71, thus closing the circuit 49 leading to the indicating or recording magnets 48 whereby the appropriate magnets will be energized which correspond to the position of the drums 41 and 85 which indicate the various digits of the total product. These magnets 48 may be used to depress the keys of an adding machine. Immediately after the magnets 48 have been energized the contact 70 passes under the 90 contact 134, thus energizing the actuating magnet 129 which operates the printing mechanism of the adding machine thereby to print or make a record of the product.

In the device shown in Fig. 8 I have illustrated a casing 408 in which the multiplying mechanism, the product-indicating members and the totalizing mechanism may be situated. The wires forming the various circuits leading from the switches and magnets 48 to the other mechanism may be enclosed in a suitable cable 409.

While I have illustrated herein a selected embodiment of my invention, yet I do not wish to be limited to the constructional features shown.

I claim:

1. In a machine for computing the product of two plural digital factors, a plurality of keys adapted to receive the "set up" of the two factors, a plurality of product-representing members, a propelling mechanism common to all the product-representing members, an arresting device associated with each product-representing member, a plurality of selector units less in number than the product-representing members but adapted to control the latter simultaneously and independently through said arresting devices, a single distributor mechanism adapted in combination with the keys and the selector units to control said arresting devices thereby to arrest the movement of each product-representing member when the latter in passing successively through various product-representing positions reaches a setting position predetermined by the actuation of the keys, and means to indicate or record the sum of the individual products obtained as aforesaid.

2. In a machine for computing the product of two plural digital factors, a plurality of setting elements which may be set to represent the digits of said two factors, a plurality of product-representing members, each constructed to represent in different selected positions the products of any two digits, means whereby said product-representing members may be moved uninterrupted from their initial to their set positions as selected by said setting elements, thereby causing said product-representing members to indicate simultaneously all the products obtained by multiplying each digit of one of said plural digital factors by all the digits of the other plural digital factor, and means to indicate by a single uninterrupted one-stage operation the total of said individual products.
3. In a machine for computing the product of two plural digital factors, the combination with a plurality of movable product-representing members, each constructed to represent in different selected positions the products of different digits, of a plurality of setting elements which may be set to represent the digits of two plural digital factors to be multiplied together, means for moving said product-representing members uninterruptedly from their initial to their final product-representing positions, means controlled by said setting elements to arrest the uninterrupted movement of the product-representing members thereby to cause them to indicate simultaneously the products of each digit of one plural digital factor by all the digits of the other plural digital factor, and means to obtain the total of said individual products simultaneously and at a single operation.
4. In a device of the class described, the combination with a plurality of rotatable product-representing members, each adapted in different selected positions to represent the product of two digits, of means to rotate all of said members simultaneously and uninterruptedly from their initial positions to said selected positions, a setting mechanism which may be set to indicate simultaneously all the digits of two plural digital factors to be multiplied together, means controlled by the setting mechanism to arrest the movement of the product-representing members in said selected positions whereby said product-representing members are constructed to represent simultaneously the individual products of all the digits of one plural digital factor multiplied by each digit of the other plural digital factor, and means controlled by said arrested product-representing members to obtain the total of all such individual products at a single operation.
5. In a device of the class described, means to effect the simultaneous multiplication of a plurality of digits of one factor by a plurality of digits of another factor, said means comprising a setting mechanism on which all the digits of the two factors may be set up prior to any other actuation of said device, in combination with a plurality of movable product-representing members each adapted in different selected positions to represent the product of any two digits, means to move said members simultaneously and uninterruptedly from their initial to their final positions as selected by the setting mechanism thereby causing them to represent simultaneously the individual products of all the digits of one factor by all those of the other factor, a plurality of bars movable toward and from said product-representing members, means to move said bars simultaneously into positions determined by the positioned product-representing members, and means actuated by said bars to indicate by a one-stage uninterrupted operation the total of said individual products.
6. In a machine for computing the product of two factors, the combination with a plurality of product-representing members, each adapted to represent in different selected positions the product of any two digits, of means to move all said members simultaneously and uninterruptedly into said selected positions to cause them to indicate the individual products obtained by multiplying each digit of one factor by all the digits of the other factor, primary totalizing mechanism to obtain the sum of such individual products, a plurality of elements adapted to control the computing mechanism of a secondary adding machine, another element adapted to actuate the printing mechanism of said adding machine, and means controlled by said totalizing mechanism to actuate said elements.
7. In a machine for computing the product of two factors, the combination with a plurality of product-representing members, each adapted to represent in different selected positions the product of any two digits, of means to move all said members simultaneously and uninterruptedly into said selected positions to cause them to indicate the individual products obtained by multiplying each digit of one factor by all the digits of the other factor, primary totalizing mechanism to obtain the sum of such individual products, a set of elements adapted to control the computing mechanism of a secondary adding machine, another element adapted to actuate the printing mechanism of said adding machine, and means controlled by said totalizing mechanism first to actuate selectively the elements of said set and then to actuate said other element.
8. In a machine for computing the product of two factors, each of two or more digits,

its, means to effect first a simultaneous and uninterrupted setting movement of a set of members adapted and sufficient to represent all the individual products of each digit of 5 one factor multiplied by each digit of the other factor and then simultaneously to obtain the addition of all the individual products.

9. In a system for computing the product of two plural digital factors, a set of individual product-representing members, means to effect a simultaneous and uninterrupted setting movement of said members thereby to obtain simultaneously the 15 individual products of one plural digital factor multiplied by each of the digits of another plural digital factor, a set of individual product-combining units, a set of indicating or recording units one for each 20 digit of the product to be indicated or recorded, a set of "carrying" units adapted when adding the digits of individual products in a sum greater than nine to carry over from one indicating or recording unit 25 to the next such figures as are required for the correct indication or recording of the product of two given factors and means whereby the carrying units operate simultaneously with the product-combining units 30 thereby to produce the correct indication at a single stage operation.

10. In a device of the class described, a plurality of indicating or recording units, one for each place of digits of two factors 35 and their product, a set of individual product-representing members, means to effect a simultaneous and uninterrupted setting movement of said members, thereby to obtain simultaneously all the individual products of each digit of one plural digital factor multiplied by each digit of another plural digital factor, means to combine the individual products thus obtained into one 40 number representing the product of the two factors, and means for communicating to the indicating or recording units all of the figures both of the two factors themselves and of their product.

11. A set of computing units adapted to be 50 given a simultaneous and uninterrupted setting movement under the co-operative control of two sets of selecting units, said selecting units comprising a plurality of keys or circuit-closing devices, one for each possible figure in each possible place of digits, in two factors of more than one figure each, and means to indicate or record the resultant 55 of the combined actuation of all computing units, so as to indicate or record the product of the two factors.

12. In a device of the class described, a plurality of figure-signifying electric circuits closeable at will in accordance with any two factors of two or more digits each of a 60 product to be computed, a set of selecting

relays controlled through said circuits, a set of computing units selectively adjustable by said relays to compute the products of each digit in one factor by each digit in the other factor, a recording or indicating device, and an accumulating mechanism adapted to communicate to said recording or indicating device the sum of the individual products obtained as aforesaid. 70

13. In a device of the class described, a set of factor-representing keys, circuit switches controlled thereby, a set of selecting relays connected to said switches, a set of simultaneously operative individual product-representing units adapted to be controlled by said selecting relays, and to be brought uninterruptedly and simultaneously into position for representing the products of each digit of one factor by each digit of 80 the other factor, and a final product-representing device adjustable from said individual product-representing units. 85

14. In a multiplying machine, a plurality of cams loosely mounted upon a shaft, an operating mechanism adapted to rotate said cams with corresponding faces of each cam normally in alinement, a ratchet wheel, a magnetically-operated pawl for each pair of cams, a plunger adapted to move against the edge of each cam, a setting device adapted to arrest each ratchet wheel with its pair of cams individually in any desired position to cause a limiting movement of said plungers corresponding with the representation 100 of the product of two figures, a sunflower switch comprising a plurality of contact segments, a trailer arm carrying a brush adapted to trail over said contact segments, the position of said brush bearing always a definite relationship to the normal position 105 of said cams, a set of figure-representing circuit switches, and a set of selecting relays associated with said sunflower switch all arranged so that after the closing of any of the said switches to represent two factors 110 the transit of the sunflower switch-brush over a pair of contacts corresponding to any two closed switches will result in actuating the magnetically-operative pawl to arrest a pair of said cams in a suitable position to 115 represent the product of two numbers.

15. In a multiplying machine, a set of primary circuits associated with individual key switches, a set of relays actuated thereby, a set of secondary circuits, each including a 120 pawl-operating magnet, controlled by said relays, a set of simultaneously-movable product-representing units, each associated with one of said pawl-operating magnets and adapted to be arrested thereby after uninterrupted movement into position to represent the product of any two digits, an adding device adapted to combine in one number representation the setting of said individual product-representing units, a result-produc- 125 130

ing device comprising tertiary circuits each of which has a figure-representing significance, all adapted to transmit to an indicating or recording device the product of any 5 two given factors.

16. In a machine for computing the product of two factors, the combination with a plurality of product-representing members, of means to actuate all of said members 10 simultaneously to bring them by an uninterrupted movement into position to indicate the individual products obtained by multiplying each digit of one factor by all the digits of the other factor, totalizing mechanism 15 to obtain the sum of such individual products which is the product of the two factors, means to make a record of the individual digits of said product, and means whereby said digits may be recorded in 20 higher or lower denominations than that in which they exist in said product.

17. In a machine for computing the product of two factors, each of two or more digits, a set of members adapted and sufficient 25 to represent all the individual products of each digit of one factor multiplied by each digit of the other factor, means common to all the product-representing members to effect and control a simultaneous setting 30 movement thereof, and totalizing means adapted to obtain the addition of all digits of like order in the partial products represented by said product-representing members and simultaneously to carry into the summation 35 of the digits of a higher order the tens figure resulting from such totalizing.

18. In a machine for computing the product of two factors, each of two or more digits, a set of members adapted and sufficient 40 to represent all the individual products of each digit of one factor multiplied by each digit of the other factor, means common to all the product-representing members to effect and control a simultaneous setting 45 movement thereof, and totalizing means adapted at a single operation to obtain the addition of all digits of like order.

19. In a machine for computing the product of two plural digital factors, a plurality 50 of digit-keys adapted to receive the "set-up" of the two factors, a set of product-representing members adapted and sufficient to represent all the individual products of each digit of one factor multiplied by each digit

of the other factor, a setting device for said members comprising a solitary propelling mechanism common to all the members, and a set of individually controlled arresting devices, one for each product-representing member, means common to all the arresting devices and associated with said digit-keys to effect a proper setting of said product-representing members, a partial-product combining mechanism associated with said product-representing members and a complete-product indicating or recording mechanism adapted to receive in the simultaneous and uninterrupted setting of all its elements the proper controlling movements to cause an indication or record of the product of the two factors.

20. In a device of the class described, the combination with a plurality of rotatable product-representing members, each adapted in different selected positions to represent 75 the product of two digits, of a setting mechanism comprising (a) keys for each digit of two plural digital factors, (b) propelling mechanism common to all the product-representing members, (c) selecting elements 80 common to various groups of product-representing members, (d) arresting elements individually associated with each product-representing member; totalizing means adapted at a single operation to obtain the sum of the 85 digits of like order represented by the product-representing members; and indicating or recording means to represent the product of the two factors.

21. In a multiplying machine, a set of 90 individual digit-keys, a set of selecting elements less in number than the number of digit-keys, a set of simultaneously-movable partial-product-representing members, each associated with said selecting elements so as 95 to be collectively yet individually controlled thereby, an adding device adapted to combine in one number-representation the setting of said partial-product-representing members, a result-producing device comprising digit-representing units; all of said mechanism being adapted to obtain the product of the two plural digital factors without the successive addition of the partial products.

In testimony whereof, I have signed my name to this specification.

RALPH W. BUMSTEAD.
